UNITED STATES PATENT OFFICE.

BENJAMIN DALTON MILLIKEN, OF SOMERVILLE, MASSACHUSETTS.

DESIGN FOR A CIGAR-LIGHTER.

SPECIFICATION forming part of Design No. 20,497, dated February 3, 1891.

Application filed April 18, 1890. Serial No. 348,554. Term of patent 3½ years.

To all whom it may concern:

Be it known that I, BENJAMIN DALTON MILLIKEN, a citizen of the United States, residing in Somerville, in the county of Middlesex and State of Massachusetts, have invented and produced a new and original Design for Cigar-Lighters, of which the following is a full, clear, and exact description, reference being had to the accompanying drawing, making part of this specification, in which is represented a perspective view of a cigar-lighter, showing my design.

The prominent features of my present design consist in a carriage-body representing a bunch of cigars located vertically with their pointed ends up, said body being mounted on wheels, with the figure of a driver and a pair of horses in front.

A is the floor or bottom of a dray or carriage, resting on an axle provided with a pair of wheels B B.

C is a representation of a bunch of cigars located vertically on the carriage-floor, the lighting ends of the cigars being downward and the pointed ends upward, with the front and rear cigars of the bunch elevated above the remainder.

What I claim is—

The design for a cigar-lighter, as herein shown and described.

Witness my hand this 16th day of April, 1890.

BENJAMIN DALTON MILLIKEN.
In presence of—
GRACE B. FRASER,
DANIEL C. BATES.
